YARN BALL SUPPORT

Clarence A. Cook, Glendale, Calif., assignor of
fifty-one per cent to Walter M. Lane, Los An-
geles, Calif.

Application October 30, 1945, Serial No. 625,629

1 Claim. (Cl. 242—130)

1

This invention relates to utility appliances and more especially to a support or hanger for yarn balls for knitting and the like.

An object of the invention is to provide a simple, practical and inexpensive yarn ball support of the character described.

Another object of the invention is to provide an efficient, foldable support for a yarn ball adapted for holding the ball in a manner to permit the yarn to be readily unwound therefrom.

A further object of the invention is to provide a foldable structure for suspending a yarn ball, having a freely rotatable pivot or spindle so that the yarn may be unwound from the ball as needed and used.

Other objects and advantages will appear and be brought out more fully in the following specification, reference being had to the accompanying drawing wherein:

Figure 1 is a perspective view of a yarn ball support embodying my invention.

Figure 2 is a top plan view of the base shown in Figure 1.

Figure 3 is an elevation view of the base shown in folded or collapsed position.

Referring more particularly to the drawing, I show a yarn ball support comprising a base 10 formed of a pair of bars 11 and 12 suitably pivoted together as by a pivot member 13 secured to bar 12 and extending through an aperture 14 in bar 11 and having a flanged head 15 adjacent bar 11.

I show a brace member 16 comprised substantially of a wire having a U-shaped formation, the end portions thereof being secured to the ends of bar 11 as by being extended through apertures therein. A pair of feet 17 may be provided and secured to the ends of bar 11 and may receive the ends of brace wire 16 if desired. As will be seen from Figures 1 and 3, feet 17 together with bar 12, when in extended or substantially right angled position with respect to bar 11, form a stable base referred to above by the numeral 10.

Brace wire 16 is formed with a loop 18 at the central upper portion thereof and a yoke member 19 is suitably suspended from loop 18. A spindle 20 is rotatably supported on yoke 19 and is formed with a loop 21 on which is suspended a ball engaging and supporting member 22. Member 22, which may comprise a resilient wire, is formed with a pair of arms 23, and a loop 24 by which it is suspended from loop 21. Arms 23 are formed with prongs 25 which extend substantially at right angles to the arms and in opposite di-

2

rections for engaging a yarn ball such as indicated at A.

The operation of the invention should be apparent from the foregoing description. A yarn ball A is suspended from supporting member 22 by contracting arms 23 together and inserting prongs 25 into the interior of the ball, which ball customarily has a somewhat cylindrical opening left by the spindle on which the yarn was wound, or such an opening can easily be made for the purpose of admitting arms 23 and prongs 25. Upon releasing arms 23, prongs 25 will engage the ball and permit free unwinding of the yarn therefrom by the free rotation of spindle 20 and the general suspension of members 19 and 22.

Base 10 will preferably be made of metal bars in order to provide a substantial weight for preventing a tipping of the base during the ordinary use. However, it will be understood that the base 10 or the brace 16 or the spindle and supporting structure 19, 20 and 22 may be made of other material than indicated or assume other shapes and arrangements than shown, and the invention is not to be limited to the present disclosure except as the subjoined claim may so provide.

Having thus described my invention what I claim and desire to secure by Letters Patent is:

A yarn ball support as described comprising a collapsible base having a pair of crossed bar members pivoted together at their center, a brace comprising a wire secured at its ends to the ends of one of said bar members, and a ball engaging and supporting member pivotally secured to said wire at its midpoint and having a pair of resilient arms adapted to engage an interior portion of a yarn ball, said base adapted to be collapsed to substantially flat condition including said brace by pivoting said bar members into parallelism.

CLARENCE A. COOK.
